UNITED STATES PATENT OFFICE.

WILLIAM S. BREMER, OF ST. LOUIS, MISSOURI.

DESIGN FOR A KICK PLATE FOR AN AUTOMOBILE.

Application filed March 29, 1922. Serial No. 1,438. Term of patent 3½ years.

To all whom it may concern:

Be it known that I, WILLIAM S. BREMER, a citizen of the United States, residing at St. Louis, in the State of Missouri, have invented a new, original, and ornamental Design for a Kick Plate for an Automobile, of which the following is a specification, reference being had to the accompanying drawing, forming part thereof.

Fig. 1 is a front view of a kick plate for an automobile embodying my invention; and

Fig. 2 is a cross-section through said plate on the line 2—2 in Fig. 1.

I claim:

The ornamental design for a kick plate for an automobile, as shown.

WILLIAM S. BREMER.
